TWO-COLOR LAP STRIPE MECHANISM

James L. Getaz, Maryville, Tenn., assignor to
 Scott & Williams, Incorporated, New York,
 N. Y., a corporation of Massachusetts

Application April 2, 1931, Serial No. 527,269

1 Claim. (Cl. 66—135)

This invention relates to circular knitting machines and more particularly to circular knitting machines adapted to make patterns by lapping plating threads around selected needles. One object of the invention is to so improve the mechanism for making the so-called lap stripe pattern that a greatly increased variety of patterns can be produced. In machines of this type the lap stripes are put in by a plurality of pattern yarn fingers revolving about a common axis, each finger also oscillating about an individual pivot point and the path of the feeding ends of the yarn fingers intersecting the needle circle. It is also an object of this invention to provide means for selectively wrapping at one wrapping point each yarn of a plurality of yarns simultaneously fed to that wrapping point about a group of one or more needles selected from a plurality of such groups of needles raised at that wrapping point by needle selecting means, such groups of needles being selected from the segment of needles comprising all needles which might be wrapped by such yarns at that wrapping point at one time and such yarns and groups of needles being associated in the formation of stripes and pattern figures at that wrapping point. It is also an object of this invention to feed such yarns at different elevations and to elevate each group of needles to an elevation corresponding to the elevation of the yarn by which the group of needles is wrapped. It is also an object of this invention to provide in a knitting machine of the type described pattern yarn fingers each of which selectively wraps a plurality of separate yarns about selected groups of needles.

The invention is shown embodied in the well known Scott & Williams type of revolving needle cylinder seamless hosiery machine.

In the drawings—

Figure 1 is a vertical section of a portion of the head of a Scott & Williams machine in which one form of this invention has been embodied.

Figure 2 is a view substantially on the line 2—2 of Fig. 1 showing in plan view the pattern yarn fingers and the cams operating them, the pattern fingers being shown in action.

Figure 3 is a view similar to Figure 2 showing the pattern yarn fingers withdrawn from action.

Figures 4 and 5 are diagrammatic views in elevation showing the relative positions of a pattern yarn finger, the yarns carried thereby and the associated groups of needles during the wrapping of the yarns about the groups of needles at one wrapping point on the needle circle; Figure 4 showing the yarn of greatest elevation retired

within the needle circle and wrapped about the group of needles raised to the greater elevation; and Figure 5 showing in lowered position the group of needles first wrapped, the yarn of lesser elevation retired within the needle circle and wrapped about the group of needles of lesser elevation.

Figures 6, 7, and 8 are diagrammatic views in plan showing the relative positions of a pattern yarn finger, the yarns carried thereby and the associated groups of needles during the wrapping of the yarns about the groups of needles; Figure 6 showing the groups of needles raised as in Figure 4 and both yarns outside of the circle of needles; Figure 7 showing the group of needles of greater elevation lowered as in Figure 5, the inner yarn or yarn of greater elevation inside and the outer yarn or yarn of lesser elevation outside the circle of needles; and Figure 8 showing both groups of needles lowered and both yarns inside the circle of needles, the pattern yarn finger being shown in broken lines to show the other parts more clearly;

Figure 9 is a fragmentary plan view, drawn to a larger scale, showing the operation of the guide on the pattern yarn finger, which deflects the yarn from the short feed tube so as to cause it to pass beneath the long feed tube.

Figures 10 and 11 are views in plan and front elevation respectively of a modified construction of yarn finger, the position of the actuating cam being indicated in broken lines in Figure 10.

This invention is shown in the drawings embodied in a circular knitting machine having a revolving needle cylinder 260, carried on a bed-plate (not shown), the needles *n* being independent of each other and vertically movable in slots in the needle cylinder as usual. There are the usual inside sinker ring 297, outside sinker cam cap (not shown) and latch ring 550 with the usual throat plate (not shown) over which the body or ground yarns are fed as usual by the main yarn fingers. In the machine shown in the drawings there is a yarn shear plate 26 inside the needle circle, this plate being carried in a non-revolvable manner by a bracket 15 on the latch ring 550. On the plate a yarn cutter and clamp 609 can be mounted if desired. The latch ring 550 is pivoted on a bracket at the rear of the machine as usual. The bracket 15 also serves to support a long vertical tube 22 for the yarns and which, in this example, is eccentrically mounted with relation to the center of the needle cylinder 260. The tube 22 carries the pattern yarn fingers 24 and extends from a point opposite

the inside sinker ring 297 to a level well above the bracket 15, there being a bobbin stand on its upper end with the pattern yarn bobbins mounted thereon as shown in my Patent #1,891,204, issued 5 Dec. 13, 1932.

The tube 22 and pattern yarn bobbins and fingers 24 are revolved in unison with the needle cylinder by suitable mechanism. Where the tube 22 passes the bracket 15 it has a horizontal bevel 10 gear g^1 keyed to it by a spline g^5 , the gear g^1 being driven as shown in my Patent No. 1,891,204.

The pattern yarn fingers 24 are supported by a plate 23 underlying them and fixed on the lower end of the tube 22. Each pattern yarn finger is 15 pivotally mounted on a stud or pin 30 secured in the plate 23 and projecting above the upper surface thereof, the upper surface of the pin being flush with the upper surface of its finger 24. The outer ends 28 of the fingers 24 are the feeding 20 ends and are curved backward, that is, assuming the common support 23 turns in a counter-clockwise direction as viewed in Figures 2 and 3, the feeding ends 28 are bent in a clockwise direction. The tails of the fingers 24 have pins or studs 29 25 projecting upwardly from them and the tails are nearly at right angles to the bodies of the fingers 24. Each stud 29 is very much closer to its pivot 30 than is the feeding end 28 of the same finger 24 and is so located that when the finger 30 24 is crossing the needle circle or moving along the outside of the circle, practically the entire movement of the stud 29 with respect to the needle circle is radial. Thus in Figure 2 the stud 29 of the finger 24 at point C is just crossing out over 35 the circle formed by the pivots 30 of the fingers 24 as the feeding end 28 of the finger moves back along the outside of the needle circle. This oscillation of the pin 29 in the region of the circle described by the pivots 30 makes it possible to 40 operate the fingers 24 by cam means which extend radially outward beyond the pivots 30 of the fingers 24. As part of these means there is an upper fixed oval cam disc 25 overlying the fingers 24 and held against rotation by screws 25a 45 and 25b (Figures 2 and 3). The cam disc 25 lies in the plane of the studs or pins 29 in the tails of the fingers 24 and forces the pins 29 outward during part of each revolution of the machine. To hold the pins 29 against the edge of the cam disc 50 25 at all times a spring band 27 is provided though it will be obvious that other suitable means could be provided. The cam disc 25 and the eccentricity, with respect to the needle circle, of the axis about which the fingers 24 revolve cause the 55 movements of the feeding ends 28 of the fingers 24 over the needle circle to wrap the yarns. It will be noted that, in the example shown, movement of a pin 29 radially inward moves the feeding end 28 of a finger 24 forward relatively to the needles or in a counter-clockwise direction; that movement of a pin radially outward causes movement backward relatively to the needles or in a clockwise direction; and that these movements of the pin 29 together with the eccentric mounting of 60 the fingers 24, with respect to the needle circle cause the movements of the ends of the fingers 24 65 across the needle circle.

When it is desired to cease patterning, the oscillation of the fingers 24 about their pivots 30 is 70 stopped by manipulating the oval cam disc 50 underlying the disc 25 and overlying the fingers 24 and, in effect, forming with the disc 25 a split cam. The disc 50 is pivoted on the screw 25b and when swung toward the closest point of approach of the support plate 23 to the needle circle 75

offers a "high face" to the pins 29 of the fingers 24 at that point thus pushing the pins 29 out and causing the feeding ends 28 of the fingers 24 to remain inside the needle circle as shown in Figure 3. The positioning of the fingers 24 inside the needle circle at this point stops all wrapping of the pattern yarns. The manipulation of the disc 50 can be effected by operating the rod 462 as shown in my Patent No. 1,891,204.

In feeding the yarns through the tube 22 it is 10 preferable to feed the yarns through separate passages formed by placing in the tube 22 a filler 15 52 whose surface contains a separate longitudinal groove 51 for the yarns for each finger. The 20 yarns are then threaded from the bottom of the tube 22 to the upper sides of the feeding ends 28 of the fingers 24 as shown in Figure 1.

The needles which are to be wrapped can be 25 raised vertically by any suitable means, but it will be noted, as shown in Figures 4 and 5 that the 30 needles which are to be wrapped at any one point are not all elevated to the same extent but are 35 divided into groups which are raised to different elevations above the needles which are not to be wrapped. In Figures 4 and 5 the needles which 40 are to be wrapped are shown divided into two groups which are raised to different elevations, the needles d of one group being raised to the greater elevation and the needles e of the other group being raised to a lesser elevation above the 45 needles f which are not to be wrapped and are left at the usual elevation. While the needles e of one group are shown divided and placed on opposite sides of needles d of the other group and each group is shown as comprising a plurality of 50 needles, it will be understood that both the arrangement of the needles and the numbers of the needles in the associated groups may be varied for the purpose of changing the stripe or pattern figure.

The pattern yarn fingers 24, as shown, are 55 each provided with a plurality of yarn feeding eyes a and b , spaced apart on the feeding ends 28 of the fingers. At the eyes a and b are feed tubes a' and b' which project different distances 60 downwardly from the finger 24 so that the yarns, as drawn away from the bottoms of the feed tubes a' and b' , are at different elevations. The difference in the elevations of the yarns of each finger 24 corresponds to the difference in the 65 elevations of the groups of needles associated with that finger 24, the yarn fed from eye a and tube a' being at an elevation to wrap the needles d of the group of needles of greater elevation and being high enough to pass above the needles e 70 of the other group. The yarn fed from eye b and tube b' is fed at such an elevation as to wrap the needles e of the other group which are at a 75 lesser elevation than the needles d . While the preferred construction in which each yarn finger 80 is provided with a plurality of yarn feeding eyes has been shown and described it is to be understood that each yarn feeding eye can be formed on a separate yarn finger as shown in Figs. 10 and 11 and the fingers associated and so operated 85 as to obtain the results produced with a plurality of eyes formed on a single yarn finger and that in its broadest aspect this invention comprises the selective wrapping of a plurality of pattern 90 yarns simultaneously fed to a single wrapping point about selected groups of needles at that wrapping point.

As shown in Figures 10 and 11, a yarn finger 95 24' is mounted on a pivot 30' carried by the support plate 23 and is provided with a pin 29' for 75

engaging the cam discs 25 and 50 and with a yarn feeding eye b^2 , yarn guide b^3 and inclined guide 60. Also mounted on the pin 30 above the yarn finger 24' is a second yarn finger 24'' provided 5 with a pin 29'' for engaging the cam discs 25 and 50 and with a yarn feeding eye a^2 and a yarn guide a^3 . In this construction the yarn guides a^3 and b^3 are of sufficient lengths to deliver yarns 10 at the same heights as the guides a' and b' of Figures 4 and 5 and the slight spacing of the pins 29' and 29'' does not effect the wrapping operation.

The operation of this device is, in general, as described in my copending application Serial 15 No. 472,354 except as regards the feeding of the yarns by the fingers 24. At the point A of Figure 2 where the yarn finger 24 is wholly within the needle circle it will be noted that each yarn goes 20 from the feeding end 28 of the yarn finger 24 to the last needle of the group that yarn wrapped 25 in the previously knit course. Following the associated groups of selected needles from the point A counter-clockwise around a revolution of the machine in Figure 2 it is seen that as the finger 30 24 travels the pin 29 comes to a portion of the cam disc 25 which does not project over the pivot 30 of the finger 24 as much as at the point A. As the spring band 27 retains the pin 29 in engagement with the cam disc 25, the feeding end 28 35 of the finger 24 travels forward past the needles to which its yarns are attached and simultaneously the feeding end 28 of the finger 24 approaches and crosses the needle circle. The relation of the eyes a and b and the feeding end 28 40 to the rest of the yarn finger 24 is such that the eye b crosses the needle circle before the eye a and both eyes a and b cross the needle circle in advance of the raised associated groups of needles d and e as shown at B^1 and B^2 in Fig. 2. The pin 45 29 under the pressure of the spring band 27 reaches its furthest point radially inward with relation to the circle described by the individual pivots 30 after the feeding end 28 of the yarn finger 24 has carried both eyes a and b across the needle circle in advance of the groups of needles d and e . The pin 29 is thereafter forced outwardly with respect to the circle of the pivots 30

by the cam disc 25 as the finger 24 moves forward which causes the feeding end 28 of the finger 24 to travel backwardly toward the groups of needles d and e and inwardly toward the needle circle. This movement of the finger 24 is continued 5 bringing the eye a back across the needle circle and to the rear of the group of needles d thus wrapping the yarn about the group of needles d . The yarn fed through eye a and tube a' , it will be noted, is at too high an elevation to engage 10 with the needles e of the other group.

As soon as the eye a has been retired across the needle circle and before the eye b is so retired, the needles d about which the yarn fed by the eye a has been wrapped are lowered by suitable operating means to the level of the needles f which are not to be wrapped and are out of the way of the yarn fed by the eye b . Further movement of the finger 24 about the cam disc 25 brings the eye b in the feeding end 28 of the finger 24 back across 20 the needle circle and in the rear of the needles e , thus bringing the yarn fed by the eye b into a different wrapping relation with the selected needles from that resulting from the movement of the yarn fed by the eye a and wrapping the 25 yarn fed by the eye b about the other or lower group of needles e . During further movement of the finger 24 to the starting point A the feeding end 28 of the finger 24 is held within the needle circle by the cam disc 25. During the movement 30 of the yarn finger from the point C to the point A the eye b with its longer feed tube b' crosses the yarn fed from the eye a and feed tube a' at an elevation above the bottom of the feed tube b' . In order to prevent the yarn fed from the 35 eye a catching on the feed tube b' the yarn finger 24 is provided with an inclined guide 60 which serves to depress the yarn fed from the eye a so that it will pass beneath the feed tube b' .

I claim—

In a knitting machine, a pattern yarn finger mounted for oscillatory movement in a horizontal plane and having a plurality of yarn feeding eyes at the feeding end thereof feeding yarns at different elevations.

JAMES L. GETAZ.
